UNITED STATES PATENT OFFICE.

ALBERT C. GETTEN, OF SANDY HILL, NEW YORK, ASSIGNOR TO THE UNION BAG AND PAPER COMPANY, OF SAME PLACE AND WATERTOWN, MASSACHUSETTS.

FLUID-SUPPLYING DEVICE.

SPECIFICATION forming part of Letters Patent No. 550,609, dated December 3, 1895.

Application filed March 8, 1894. Serial No. 502,809. (No model.)

To all whom it may concern:

Be it known that I, ALBERT C. GETTEN, a citizen of the United States, and a resident of Sandy Hill, Washington county, State of New York, have invented certain new and useful Improvements in Fluid-Supplying Devices, of which the following is a specification, reference being had to the accompanying drawings, forming part hereof.

10 This invention relates to devices for supplying fluids to machines in which these fluids are to be used.

My invention has been embodied in connection with paper-bag machinery and in 15 means for supplying paste to the paste boxes or reservoirs of such machines, and I will particularly describe herein the best means that I have adopted in thus carrying my invention into practice.

20 Paper-bag machines use large quantities of paste. Each machine is usually provided with two paste boxes or reservoirs, from which the paste is fed to and suitably applied upon the bags made by the machine. One of these 25 paste-boxes is designated the center-seam paste box and the other is designated the head or bottom paste box. Each one of these two paste-boxes in some factories uses paste of a different consistency, the center-seam paste 30 being quite thin and the head-paste quite thick. Prior to my invention these paste-boxes were filled by the operatives as occasion required by pouring the paste into the boxes from pails. Each machine had two 35 pails, one for the head-paste and one for the center-seam paste, and these pails were replenished from a suitable mixer and reservoir. This procedure was extremely wasteful, uncleanly, and unsatisfactory. The paste would 40 be spilled about on the floor, and it would become hard and dry from exposure to the air on the sides of the pails. To keep the paste in proper condition, it was necessary to wash out these pails every day, and this work of 45 cleaning was extremely laborious and wasteful of the paste. In large factories having thirty or forty machines the wastefulness of the old method was especially notable and all the objectionable features above noted were

more strongly accentuated. There was also 50 another and great objection to the old method, and it was that frequently, through the carelessness of the attendants, the paste-boxes in the machine would run dry for periods sometimes of a few minutes, sometimes longer, and 55 hundreds and even thousands of bags would be properly folded and apparently properly made, but without a particle of paste upon them, and these bags would be packaged, shipped, and delivered without discovery of 60 their defect until in the hands of the user. This latter objection is a most troublesome one in business arrangements, and, notwithstanding the greatest care in supervision of the operatives, was not overcome until the 65 present invention substituted in place of the manual work of the operatives automatic means for uniformly conveying to the paste-boxes a regulated supply of paste.

In the embodiment of my invention herein 70 described the paste is conveyed by a conduit from a main reservoir to the several machines in which it is to be used, and means are provided for regulating the quantity of paste supplied to each paste-box in accordance with the 75 rate of consumption in each machine, said means being controlled by the movements of the respective machines and operated by some moving part of the machine.

As paste is a thick and somewhat viscous 80 fluid, it is more difficult to manage and control than a thin fluid; but in the means embodying my invention the paste is allowed to flow in considerable volume for short periods of time, and this is repeated at intervals in 85 the operation of each machine. This is accomplished by providing a cock or valve in a branch of said conduit, suitably located in proximity to the paste-box of each machine, and operating this cock or valve intermittently 90 by connection with some moving part of the machine, so that the cock or valve at intervals is opened to allow a quantity of paste to flow into the paste-box and is then closed and remains closed for a period. These 95 operating means are capable of delicate adjustment, so that the degree of opening of the cock or valve or the duration of that opened

condition or both degree and duration may be adjusted to correspond with the rate of consumption of the machine.

For the purpose of supplying the two kinds of paste when required—to wit, the head-paste and the center-seam paste—I have fitted up two supplying and circulating systems, one system connected with a reservoir for the thicker or head-paste and the other system connected with a reservoir for the thinner or center-seam paste, and these two systems are entirely independent of each other, and both are operated in substantially the same manner.

15 The accompanying drawings, to which I will now refer, illustrate embodiments of my invention.

Figure 1 is an end elevation of a portion of a paper-bag machine, including the center-seam paste-box, and showing a portion of the conduit and my improved means for regulating the supply of paste to the paste-box. Fig. 2 is a part plan view of the same. Fig. 3 is a side elevation showing a modified construction of the device for operating the cock or valve, and Fig. 4 is a plan view of a portion of the same. Fig. 5 is an end elevation showing a head-paste box and a portion of the conduit and a construction of my improved means 25 for regulating the supply of paste to this paste-box. Fig. 6 is an enlarged sectional view of the adjustable tappet or cam. Fig. 7 is an elevation on a reduced scale showing a main reservoir and a portion of the conduit 30 and the means for circulating the paste in said conduit.

The main reservoir *a*, Fig. 7, in the embodiment of my invention shown is charged with paste and is provided with suitable devices—40 such as the rotating arms *b*, operated by the vertical shaft *c*—to keep the paste properly mixed and of uniform consistency and to prevent the formation of lumps therein. The conduit *d* extends from the lower part of said reservoir *a* and is provided with branches *ff*, extending in proximity to the respective machines, and this conduit returns to the main reservoir *a*, so as to carry the excess of paste back to the reservoir, as shown. The conduit *d* has interposed therein a force-pump *d'*, operated by the crank *d²* on the shaft *d³*. The shaft *d³* is suitably operated and may be connected with the vertical shaft *c* by bevel-gears *c' c²*, as shown, or otherwise, or the two shafts *d³* and *c* may be independently operated in any suitable manner. A check-valve 45 at *e* co-operates with the pump-piston in forcing the paste through the conduit, and an air-chamber *e'* performs the usual function of such devices. The conduit preferably inclines slightly downward from the point at which the air-chamber *e'* is located, so that gravity will assist the flow of the paste therethrough and so that the conduit will drain 50 itself when water or fluid is used to wash it.

Fig. 7 illustrates the circulating system for either center-seam or head paste. When these

two consistencies of paste are to be supplied, the system shown in Fig. 7 is duplicated, and thus two separate systems, each like that shown in Fig. 7, are employed, one of the systems having branches in proximity to the center-seam-paste boxes of the machines and the other system having branches in proximity to the head-paste boxes of the machines. 75

It is, of course, evident that other arrangements than those shown may be employed and that the paste may be forced through the conduit by gravity or other pressure-producing means or in any other suitable manner. 80

The branches *ff* of the conduit are shown in Figs. 1 and 5 in their proper relation to the paste-boxes of the machines—that is to say, with their lower extremities above the paste-boxes, so that the paste will be prop- 85 erly dropped into the boxes.

I will first describe the construction shown in Figs. 1 and 2 of the devices for regulating the supply of paste to the boxes. The paste-box *g* (shown in Fig. 1) is that employed for supplying the center-seam paste of the bag and contains the usual rotating paste-supplying disk *g'*. The strip of paper *i* from the roll is pulled through the rollers *h* and *h'* by the other parts of the machine, and thus these 90 rollers are rotated by the friction of the paper. A worm *j* is secured upon the end of the upper roller *h* and meshes with a worm-wheel *j'*, having bearings in the bracket-piece *j²*, which is suitably secured to the frame 95 *k* of the machine. A collar or disk *l* is formed or secured upon the shaft of the worm-wheel *j'* and is provided with a cam projection or tappet *l'*, and this tappet *l'* comes in contact at every revolution with the pivoted lever *l²*. 100 This lever *l²* is pivoted upon the bracket-piece *l³* and has a bolt-and-slot connection *l⁴* with the bracket-piece *j²*, so as to be vertically adjustable. An adjustable stop *l⁵* is provided, secured to the bracket-piece *l³*, and the spring *l⁶* tends to hold the pivoted lever *l²* against this stop. The pivoted lever *l²* is connected by a rod *m* with an arm or handle *n'* of a cock *n*, of any suitable and usual construction, which is interposed in the branch 110 *f* of the conduit. It will be seen that the tappet *l'* at every revolution of the worm-wheel *j'* will actuate the pivoted lever *l²* and move it and the rod *m* in the direction indicated by the arrow, and this movement will turn the 115 cock *n*, so as to open the passage through the same. After the tappet *l'* has released the lever *l²* it will be pulled back by the spring *l⁶* to the position shown. During the period when the cock *n* is open a portion of paste 120 will flow into the paste-box; but this flow will be checked by the closing of the cock *n*. Thus at every revolution of the worm-wheel *j'* the cock will be open for a short period and a definite quantity of paste will flow into the 125 paste-box *g*. By adjusting the bracket *l³* the amount of paste supplied at these times may be regulated to the desired extent, and by this adjustment the amount of paste supplied 130

will be made equal to the amount used in the machine. When the machine is started, the operator will first open the cock n and permit sufficient paste to enter the box to partially or wholly fill the same, and thereafter, as the machine is used, the regulating device will supply the amount of paste consumed or used in the operation of the machine, so as to constantly maintain the amount of the initial charge of the paste-box. The connection of the rod m with the arm n' permits the rod to be lifted at any time, so to be disconnected from the arm n' . A rest or stop n^2 is provided to support the rod when it is disconnected from the arm n' and to prevent the arm n' from being moved out of its working position or from falling down. A suitable brace q holds the end of the branch pipe f in desired position over the paste-box.

In Figs. 3 and 4 another construction of the devices for operating the cock or valve is shown, adapted to other constructions of paper-bag machines. In this construction a rotating shaft of the machine h^2 is provided with a worm j^3 , which meshes into a worm-wheel j^4 , having bearings in the bracket j^5 , secured to the frame of the machine k . The tappet or cam in this construction is a plate o , having an inclined working surface, and is adjustably clamped to the collar o' , which is formed or secured upon the shaft of the worm-wheel j^4 . The pivoted lever l^7 is mounted upon the bracket l^8 , and its movement is controlled by the stop l^9 and the spring l^{10} , acting in conjunction with the tappet or cam, all in substantially the same manner as described in relation to Fig. 1, and the rod m' , which is connected to the arm of the cock or valve, is pivoted to the lever l^7 below the point at which the lever is pivoted instead of above that point, as in Fig. 1. The extent and duration of the movement of the rod m' are adjusted by adjusting the position of the tappet o upon the collar o' .

The construction of regulating device shown in Figs. 5 and 6 is adapted to the head-paste box of the machine shown in Fig. 1. A rotating shaft of the machine h^4 is provided with a worm j^6 , meshing in a worm-wheel j^7 , and an adjustable tappet p is mounted on a collar of the worm-wheel shaft and works against a pivoted lever l^2 of exactly the same construction as shown in Fig. 1 and controlled by a stop l^5 and spring l^6 , also of the same construction as shown in Fig. 1. This lever l^2 is carried by the bracket l^{11} , which in this case is not adjustable, as the adjustment is provided by the tappet p , which screws into its collar and has a jam-nut p' (see Fig. 6) for holding it in the desired position. A rod m^2 is connected at one end to the lever l^2 and at the other end to the arm n^8 of a cock n^4 , interposed in the branch f of the conduit, which is arranged above the paste-box g^2 . A stop n^5 is provided, which performs the same function as the stop n^2 of the construction shown in Fig. 1, and the rod m^2 is constructed so

that it may be lifted clear of the arm n^3 , when desired. A suitable brace q' holds the end of the branch pipe f in desired position over the paste-box.

The constructions shown in the drawings and above described illustrate three slightly-different structures wherein my invention has been embodied. In applying my improvements to other constructions of machines other modifications will be made, depending upon the location and operation of the moving part of the machine to which the regulating device is connected.

It is, of course, evident that other devices than cocks, as shown in the drawings, may be employed for providing a variable opening for the paste or other fluid—as, for instance, valves of suitable construction; also, that other mechanisms may be used to actuate the cocks or valves.

In supplying the fluid to the machines in accordance with my invention, as above described, there is practically no waste of the fluid. It does not have to be carried about by hand nor transferred by hand from one receptacle to another. It is circulated within a closed conduit and not exposed to the air while in the conduit, so that it is protected from the drying and deterioration that would otherwise take place. No dependence is placed upon the operator in the work of keeping up the supply to the boxes or reservoirs of the machine, as the mechanism, after having been once adjusted to the rate of consumption of the machine, supplies the fluid in accordance with that rate of consumption, operating periodically when the machine is running and stopping when the machine is stopped, and at all times supplying the fluid in proportion to the rate of operation of the machine.

What I claim, and desire to secure by Letters Patent, is—

1. The combination with a machine for applying paste or other fluid to paper or other fabric, of a main reservoir for the fluid, a fluid supplying conduit extending therefrom through which conduit the fluid is caused to flow, a branch extending from said conduit in proximity to a box or reservoir in said machine, a roller moving with the paper or other fabric, and intermittently operating means actuated by said roller for regulating the supply of fluid from said branch, substantially as set forth.

2. The combination with a machine for applying paste or other fluid to paper or other fabric, of a main reservoir for the fluid, a fluid supplying conduit extending therefrom through which conduit the fluid is caused to flow, a branch extending from said conduit in proximity to a box or reservoir in said machine, and a cock or valve in said branch, a roller moving with the paper or other fabric and means actuated by said roller for operating said cocks or valves so as to regulate the supply of fluid, substantially as set forth.

3. The combination with a machine for applying paste or other fluid to paper or other fabric, of a main reservoir for the fluid, a fluid supplying conduit extending therefrom through which conduit the fluid is caused to flow, a branch extending from said conduit in proximity to a box or reservoir in said machine, and a cock or valve in said branch, a roller moving with the paper or other fabric and means actuated by said roller for intermittently opening said cock or valve so as to periodically supply a desired portion of said fluid, substantially as set forth.
4. The combination with a machine for applying paste or other fluid to paper or other fabric, of a main reservoir for the fluid, a conduit leading therefrom and returning thereto, means for maintaining a circulation of the fluid in said conduit, a branch extending from said conduit in proximity to a box or reservoir in said machine, a roller moving with the paper or other fabric and intermittently operating means actuated by said roller for regulating the supply of fluid from the said branch, substantially as set forth.
5. The combination with a machine for applying paste or other fluid to paper or other fabric, of a main reservoir for the fluid, a conduit leading therefrom and returning thereto, means for maintaining a circulation of the fluid in said conduit, a branch extending from said conduit in proximity to a box or reservoir in said machine, and a cock or valve in said branch, a roller moving with the paper or other fabric and means actuated by said roller for operating said cock or valve so as to regulate the supply of fluid, substantially as set forth.
6. The combination with a machine for applying paste or other fluid to paper or other fabric, of a main reservoir for the fluid, a conduit leading therefrom and returning thereto, means for maintaining a circulation of the fluid in said conduit, a branch extending from said conduit in proximity to a box or reservoir in said machine, and a cock or

valve in said branch, a roller moving with the paper or other fabric and means actuated by said roller for intermittently opening said cock or valve so as to periodically supply a desired portion of said fluid, substantially as set forth.

7. The combination with a machine for applying paste or other fluid to paper or other fabric, of a conduit for supplying the same, a cock or valve in said conduit, a rod connected to the said cock or valve and a pivoted lever connected to said rod, a roller moving with the paper or other fabric and intermediate means whereby said lever is actuated thereby to periodically open and close said cock or valve, substantially as set forth.

8. The combination with a machine for applying paste or other fluid to paper or other fabric, of a conduit for supplying the same, a cock or valve in said conduit, a rod connected to an arm of said cock or valve, a pivoted lever connected to said rod, a roller moving with the paper or other fabric, a tappet or cam operated thereby and constructed so as to periodically operate said lever, and means for retracting the lever after it has been operated by said tappet or cam, substantially as set forth.

9. The combination with a machine for applying paste or other fluid to paper or other fabric, of a conduit for supplying the same, a cock or valve in said conduit, a rod connected to an arm of said cock or valve, a pivoted lever connected to said rod, a roller moving with the paper or other fabric, a tappet or cam operated thereby and constructed so as to periodically operate said lever, and a spring for retracting said lever and a stop against which it is held by said spring, substantially as set forth.

This specification signed and witnessed this 1st day of March, A. D. 1894.

ALBERT C. GETTEN.
